UNITED STATES PATENT OFFICE.

GOMER W. PRICE, OF OAKLAND, CALIFORNIA, ASSIGNOR TO HENRY L. SMITH, OF SAN RAFAEL, CALIFORNIA.

STEERING-WHEEL FOR TRACTION-ENGINES.

1,151,713.

Specification of Letters Patent. Patented Aug. 31, 1915.

Application filed December 29, 1914. Serial No. 879,567.

To all whom it may concern:

Be it known that I, GOMER W. PRICE, a citizen of the United States, residing at Oakland, in the county of Alameda and State of California, have invented certain new and useful Improvements in Steering-Wheels for Traction-Engines, of which the following is a specification.

My invention relates generally to traction engines and similar heavy vehicles in which a single front wheel is used as a tiller or steering-wheel, and it relates particularly to said front wheels and their mounting construction.

The front-wheel construction generally in use, where a single wheel is employed as a tiller, assumes one of several forms. The wheel is either mounted in a rigid or non-spring frame, or it has a spring at each end of the wheel axle, or it has a conical yoke coming to a point overhead and there spring mounted.

Experience has shown that the spring mounted tiller or steering-wheel is a necessity, but the types of spring suspension so far adopted have been very unsatisfactory, owing to the peripheral tongue or projection on the tread of the wheel, which tongue is supposed to set or bite deep enough in the soil to be of use for steering purposes. When this tongue is on hard ground, or when in soft ground, it sinks deep enough to rest the face of the wheel on the soil its full width, the result is that the wheel will tilt so that the tongue and one edge of the face of the wheel only will bear on the ground. If the wheel is turned to the right, then the tongue and the right hand edge of the wheel face will bear on the ground. If turned to the left, the left hand edge and the tongue will bear on the ground and will remain in this position until turned in the opposite direction. This results in making it practically impossible to guide or steer the tractor in a straight line or to make proper turns.

The object of my invention is to overcome this difficulty, and to this end my invention consists in the novel steering or front-wheel constructions which I shall hereinafter fully

describe by reference to the accompanying drawings in which—

Figure 1 is a plan view of my steering-wheel construction in its preferred form. Fig. 2 is an elevation of the same. Fig. 3 is a plan view of a modified construction. Fig. 4 is an elevation of the same.

Referring first to Figs. 1 and 2,—1 is the turn-table, usually made of channel iron with the flanges extending outwardly so that it may receive and carry a steering chain 2. This turn-table also carries the weight of the front portion of the tractor frame, by means of a number of suitable anti-friction hangers. One of these hangers 3, I show in Fig. 2. It carries a roller 4 above and a roller 5 below the channel iron turn-table, and a third roller 6 running over the face of the channel flanges. Across the turn-table extend the rigid parallel bars 7 lying in chords on each side of a diameter, said bars being rigidly attached at their ends to the inner face of the turn-table.

8 is the steering wheel having the median circumferential tongue or projection 9. 10 is the wheel frame diametrically embracing said wheel and in which the wheel is mounted by its shaft or axle 11, which is fastened rigidly in the frame, and on which the wheel rotates.

On the forward end of the frame 10, are the uprising extensions 12, one on each side. These extensions rise within the turn-table bars 7 near the forward ends thereof and they are connected with said bars by the hinges 13.

The rear end of the wheel frame 10 is properly guided and braced by the braces 14 depending from the turn-table, said braces having their lower ends connected by a cross rod 15. The frame 10 at the middle of its rear end carries a socket-seat 16, for a heavy spiral spring 17, the upper end of which is seated in a socket 18 secured to the turn-table.

19 indicates the spoke system of the wheel.

When the tractor is in motion, it propels the turn-table through its hangers 3, said turn-table being readily rotatable by reason

of the rollers of the hangers. The steering wheel being connected with the turn-table as described is propelled thereby; and the front end of the tractor is thus supported by said 5 wheel, through the hinges 13 and spring 17, which also compensate for any variation in the contour of the ground. This construction by its lateral rigid bracing of the wheel, entirely overcomes the tendency of said 10 wheel to ride on one side or the other.

Referring now to the modification shown in Figs. 3 and 4, I have indicated like parts by the same numerals. In this form, however, the steering-wheel frame, instead of 15 being hinged to the turn-table bars through the intervention of uprising extensions, is hinged directly to said bars, preferably by a through pintle rod 13' running through a distance piece 20. This form of the construction while giving the necessary rigid lateral bracing to effect the result desired, namely, to overcome the tendency of the wheel to ride on one side or the other, limits the diameter of the tiller wheel, or, if the 20 maximum diameter be used as is sometimes required in plowing in very soft soils, then the turn-table becomes too large in diameter to be practical. For this reason the construction illustrated in Figs. 1 and 2 is to be 25 preferred, for by reason of its extensions 12, the wheel frame at its forward end may drop below and therefore extend fully to or even project beyond the turn-table, this providing for a wheel of larger diameter without increasing the diameter of the turn-table. 30

I claim:—

1. In steering-wheel construction for vehicles, the combination of a turn-table; means 40 for rotatably connecting said turn-table with the vehicle frame; cross bars rigidly secured to said turn-table; a steering wheel; a rigid frame diametrically embracing and carrying said wheel; a hinge connection between 45 one end of the wheel frame and the cross bars of the turn-table; and a resilient bearing between the other end of the wheel frame and said turn-table.

2. In steering-wheel construction for vehicles, the combination of a turn-table; means 50 for rotatably connecting said turn-table with the vehicle frame; cross bars rigidly secured to said turn-table; a steering wheel; a rigid frame diametrically embracing and carrying 55 said wheel; a hinge connection between one end of the wheel frame and the cross bars of the turn-table; and a resilient bearing seated centrally between the other end of the wheel frame and said turn-table.

60 3. In steering-wheel construction for vehicles, the combination of a turn-table; means for rotatably connecting said turn-table with the vehicle frame; cross bars rigidly secured to said turn-table; a steering wheel; a rigid

frame diametrically embracing and carrying 65 said wheel; a hinge connection between one end of the wheel frame and the cross bars of the turn-table; fixed guides depending from the turn-table, connected at their lower ends by a rod, said guides passing 70 down on each side of the wheel frame at its other end; and a spring bearing between said end of the wheel frame and the turn-table.

4. In a steering-wheel construction for vehicles, the combination of a turn-table; means 75 for rotatably connecting said turn-table with the vehicle frame; cross bars rigidly secured to said turn-table; a steering wheel; a rigid frame diametrically embracing and carrying 80 said wheel, said frame throughout its length lying below the level of the turn-table and having near one end extensions which rise within the turn-table to its cross bars; hinge connections between said extensions 85 and the cross bars of the turn-table; and a resilient bearing between the other end of the wheel frame and said turn-table.

5. In a steering-wheel construction for vehicles, the combination of a turn-table; means 90 for rotatably connecting said turn-table with the vehicle frame; cross bars rigidly secured to said turn-table; a steering wheel; a rigid frame diametrically embracing and carrying 95 said wheel, said frame throughout its length lying below the level of the turn-table and having near one end extensions which rise within the turn-table to its cross-bars; hinge connections between said extensions and the cross bars of the turn-table; and a 100 resilient bearing seated centrally between the other end of the wheel frame and said turn-table.

6. In a steering-wheel construction for vehicles, the combination of a turn-table; means 105 for rotatably connecting said turn-table with the vehicle frame; cross bars rigidly secured to said turn-table; a steering wheel; a rigid frame diametrically embracing and carrying 110 said wheel, said frame throughout its length lying below the level of the turn-table and having near one end extensions which rise within the turn-table to its cross bars; hinge connections between said extensions and the cross bars of the 115 turn-table; fixed guides depending from the turn-table, connected at their lower ends by a rod, said guides passing down on each side of the wheel frame at its other end; and a spring bearing seated centrally between said 120 end of the wheel frame and the turn-table.

7. In a steering-wheel construction for vehicles, the combination of a turn-table; hangers depending from the vehicle frame and provided with rollers, one bearing on 125 the upper face, one on the lower face and one on the outer face of the turn-table, whereby said turn-table is rotatably con-

ected with the vehicle frame; bars rigidly secured to said turn-table; a steering wheel; a rigid frame diametrically embracing and carrying said wheel; a hinge connection between one end of the wheel frame and the cross bars of the turn-table; and a resilient bearing between the other end of the wheel frame and said turn-table.

In testimony whereof I have signed my name to this specification in the presence of 10 two subscribing witnesses.

GOMER W. PRICE.
